**COMBINED HANDLE, BATTERY AND MOTOR
HOUSING FOR AN ELECTRIC SAFETY RAZOR
OR SIMILAR ARTICLE**

Glen R. Sulisky, 2325 W. 13 Mile Road,
Royal Oak, Mich. 48073

Filed Sept. 28, 1971, Ser. No. 184,649

Term of patent 14 years

Int. Cl. D28—03

U.S. Cl. D95—3 A

FIG. 1

FIG. 3

FIG. 2

FIG. 4

FIG. 1 is a perspective view of a combined handle, battery and motor housing for an electric safety razor or similar article, showing my new design;

FIG. 2 is a side elevational view, the appearance being substantially the same from all sides;

FIG. 3 is a top plan view; and

FIG. 4 is a bottom plan view thereof.

I claim:

The ornamental design for a combined handle, battery and motor housing for an electric safety razor or similar article, as shown and described.
